CHARLES TREZONA, OF ELY, AND EDWARD A. MALMGREN, OF DULUTH, MINNESOTA

NONSPILLING-POCKET GATE

Application filed April 23, 1928. Serial No. 272,123.

This invention pertains to non-spilling pocket gates, and more particularly to loading and measuring means actuated to prevent spilling or dribbling from the device during 5 loading operations.

It is desirable in loading conveyors from any source to transfer the material from the source to the conveyors without spilling the material around the conveyor and to fill the 10 same to predetermined amounts. In underground mine operations, ore or the like is hoisted from the lower levels by means of a skip, which skip travels in a shaft which is oftentimes considerably larger in cross-section 15 than the cross-sectional area of the skip. The skip is loaded at the working level from an underground pocket which is to receive the ore from mine cars operating on the level above. Heretofore, it has been the practice 20 to provide the bottom or mouth of the pocket with a gate of the finger type, which gate was operated by any suitable mechanism. With such construction, loading takes place after the skip has been stopped at the desired point 25 below the pocket by merely opening the gate and allowing the ore in the pocket to slide directly into the skip. However, in discharging from the pocket to the skip, the ore has to pass over the intervening space between the 30 end of the chute and the skip, and in completing this operation, there is always a dribble of ore past the skip down the shaft, the accumulation of which is of course objectionable and has to be removed from time to 35 time.

It is therefore an object of this invention to provide a non-spilling pocket gate construction to eliminate spillage of material, especially in mine operations.

Another object is to provide a device for 40 measuring quantities of ore or the like and operative to discharge substantially all of said material into a conveyor.

Still another object is to provide discharge 45 apparatus associated with the measuring pocket whereby the material will not be discharged from the pocket until guiding means for said material has been located to direct the material into a conveyor.

A further object is to provide discharge

mechanism associated with the measuring pocket wherein the closure for the measuring pocket is operable automatically by directing means adapted to guide the flow of material from the pocket to the conveyor. 55

A still further object is to provide a non-spilling pocket gate which is simple, cheap to manufacture, easily removed, convenient to operate and fulfills all requirements of manufacture and service. 60

With these and various other objects in view, the invention consists of certain novel features of construction and operation as will be more fully described and particularly pointed out in the specification, drawings and claims appended hereto. 65

In the drawings, wherein like reference characters are used to designate like parts—

Figure 1 is a sectional side elevation of the device, showing the same in inoperative position; 70

Figure 2 is a front elevation of the device illustrated in Figure 1; and

Figure 3 is a sectional side elevation of the device illustrated in Figure 1, the same being 75 shown in operative or discharge position.

In the device shown, the discharge pocket 10 is constructed having a front wall 11 associated with a side wall 12 of a mine shaft, the same being located in a position so that it will 80 not interfere with the operation or travel of the skip 13 which is adapted to travel within the shaft and be loaded from said pocket. The pocket is provided with a reinforced rear wall 14 sloping toward the shaft, the lower portion of said wall being spaced from the 85 lower edge of the wall 11, providing an opening which is adapted to be closed by means of the gate 15 hinged to the wall 11 as at 16, the gate being formed with guide plates 17 extending and overlapping the wall 14 so as to provide shields for the material in discharge position, preventing the material from flowing from the sides of the pocket. 90

The pocket is also provided with side walls 18 for completing the pocket, which side walls may form a convenient attachment for horizontal and vertical plate members 19 and 20 serving to secure the device within the pocket provided in the mine or the like. The pocket 95

is also provided with a chute 21 of the tunnel type, having an end opening 22 located within a further cut 23 of the device-containing space. The chute is hinged as at 24 and overlaps the bottom and sides of the measuring pocket 10 in order to prevent leakage from the side of the chute when in operation.

A portion of the front wall 25 of the chute overlaps the lower edge of the gate 15 in order to maintain the same in closed position when the device is inoperative, the chute being preferably moved by means of engine 26 which may take the form of a cylinder and piston having a piston rod 27 pivoted as at 28 to the chute, the piston being actuated by fluid supplied at selected ends of the cylinder by means of fluid lines 29 and 30 connected to the operating valve 31 located above the level 32 for convenient operation thereof through the lever 33.

The pocket is provided with a frame 34 which may support locking mechanism for the gate 15. Said mechanism may take the form of a toggle including a bellcrank 35 pivoted at 36 to the frame 34, one arm 37 of the bellcrank being pivoted as at 38 to a link 39, the other end of which is pivoted as at 40 to the shield 17 of the gate, the link and bellcrank being so arranged that they lock the door in closed position. A spring or counterweight may be attached to the end of the arm 35, if desired, for the purpose of urging the gate into closed or open position. The other arm 41 of the bellcrank is attached to a portion of the chute such as by means of a flexible chain 42. The pocket may also be provided with any usual chair operating mechanism for the skips, such as the lever 43 (the manner of the conventional mechanism not being illustrated).

In operation then, when it is desired to load a skip 13, the same being positioned below the chute 21, such as illustrated in Figure 3, fluid is admitted to the valve 31 through the conduit 44, and the valve is operated to permit the fluid to pass through the pipe 29 to one end of the cylinder 26 moving the piston and piston rod outwardly, causing outward movement of the chute 21. Just as the lower lip of the chute passes the vertical plane through the adjacent side of the skip, tension is applied to the arm 41 through the chain 42 which moves the bellcrank to break the toggle, thereby unlocking the pocket gate 15 and allowing the weight of the ore in the pocket to force the gate open. The ore then passes freely into the skip without dribbling down the shaft, the pocket gate being preferably of such size that it may be totally discharged into the skip, filling the same.

It will be noticed that the pocket gate 15 is always overlapped by the outer face of the chute, thereby preventing any tendency of spilling. When the pocket has been discharged, fluid is admitted through the pipe 30

to the other end of the cylinder, causing movement of the chute inwardly, the outer face of the chute engaging the lower end of the gate 15, moving the same back to its normal or closed position, at which time the toggle levers are dropped or forced into their closed or locking positions.

When the chute is not in its full open position, the balance of the gate 15 is such that it will not normally close of its own accord but will remain sufficiently open to allow all dribble to pass inside the chute and thence into the skip, and further, the center of gravity of the chute 21 is such that when moving free from restraint by the engine, it will not only return itself to the position indicated in Figure 1, but will also force the gate 15 into its normally closed position, the object of this being that if for any reason the engine becomes inoperative or is detached from the chute, the chute will always of its own accord assume a position where it will not be struck by the moving skip.

It is to be understood that I do not wish to be limited by the exact embodiment of the device shown, which is merely by way of illustration and not limitation, as various and other forms of the device will of course be apparent to those skilled in the art.

We claim:

1. In a device of the character described, a measuring pocket including a front wall, vertical side walls and an inclined bottom wall, the lower edge of said inclined bottom wall being arranged in the plane of said front wall, a gate for controlling the discharge from said pocket, said gate including a front wall arranged to form a substantial prolongation of the front wall of said pocket and side walls adapted to overlap the side walls of said pocket, said gate being pivotally mounted to freely hang in a slightly open position, means normally holding said gate in closed position, means for releasing said gate to permit said gate to be opened by the weight of material in said pocket.

2. In a device of the character described, a measuring pocket including a front wall, vertical side walls and an inclined bottom wall, the lower edge of said inclined bottom wall being arranged in the plane of said front wall, a gate for controlling the discharge from said pocket, said gate including a front wall arranged to form a substantial prolongation of the front wall of said pocket and side walls adapted to overlap the side walls of said pocket, said gate being pivotally mounted to freely hang in a slightly open position, means normally holding said gate in closed position, means for releasing said gate to permit said gate to be opened by the weight of material in said pocket, said last named means comprising a directing chute pivotally mounted to be swung into oper-

ative position to direct the discharge of material from said pocket.

3. In a device of the character described, a measuring pocket including a front wall, 5 vertical side walls and an inclined bottom wall, the lower edge of said inclined bottom wall being arranged in the plane of said front wall, a gate for controlling the discharge from said pocket, said gate including 10 a front wall arranged to form a substantial prolongation of the front wall of said pocket and side walls adapted to overlap the side walls of said pocket, said gate being pivotally mounted to freely hang in a slightly 15 open position, means normally holding said gate in closed position, means for releasing said gate to permit said gate to be opened by the weight of material in said pocket, said last named means comprising a directing 20 chute pivotally mounted to be swung into operative position to direct the discharge of material from said pocket, said chute including a front wall arranged to form substantial prolongation of the front wall of 25 said pocket when in inoperative position and side walls arranged to overlap the side walls of said gate.

Signed at Duluth, Minnesota, this 17th day of April, 1928.
